Primary Examiner — Susan Bennett Hattan*Assistant Examiner* — Brett Miller*(74) Attorney, Agent, or Firm* — Taylor J. Ross(57) **CLAIM**

The ornamental design for an arancini maker, as shown and described.

DESCRIPTION

FIG. 1 is a top, front and left side perspective view of an arancini maker showing our new design;

FIG. 2 is a bottom, rear and left side perspective view thereof;

FIG. 3 is a top plan view thereof;

FIG. 4 is a bottom plan view thereof;

FIG. 5 is a front elevation view, the rear elevation being a mirror image thereof;

FIG. 6 is a left side elevation view thereof;

FIG. 7 is a right side elevation view thereof;

FIG. 8 is a top, front and left exploded view of the arancini maker of FIG. 1; and,

FIG. 9 is a bottom, front and left exploded view of the arancini maker of FIG. 1.
